(57) **CLAIM**

The ornamental design for a compact high definition television antenna, as shown and described.

DESCRIPTION

A related application is U.S. Patent Application Ser. No. 12/474,119 filed May 28, 2009 entitled compact high definition digital television antenna.

FIG. 1 is a perspective view of a television antenna showing our new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The mounting hardware and signal pass throughs are shown in broken lines to depict environmental subject matter only and form no part of the claimed design.
